UNITED STATES PATENT OFFICE.

LEWIS H. HITCHCOCK, OF KNOXVILLE, TENNESSEE.

WALL-PAPER MACHINE.

1,274,040

Specification of Letters Patent. Patented July 30, 1918.

Application filed August 7, 1917. Serial No. 184,972.

To all whom it may concern:

Be it known that I, LEWIS H. HITCHCOCK, a citizen of the United States, residing at Knoxville, in the county of Knox, State of Tennessee, have invented a new and useful 5 Wall-Paper Machine; and I do hereby declare the following to be a full, clear, and exact description of the invention, such as will enable others skilled in the art to which 10 it appertains to make and use the same.

This invention relates to a wall-paper hanging machine, and an object thereof is to provide a comparatively simple, efficient, compact and practical machine of this kind 15 for pasting, trimming and applying wall paper to the ceiling or side wall of a room, and finally cutting the strip of paper.

A further object of the invention is to provide an improved machine having a 20 paste receptacle over an opening of which the wall paper is drawn, in combination with a paste feed follower in the receptacle for feeding the paste toward and upon the paper, as it passes said opening.

25 A further object of the invention is to provide improved cutting means for severing the desired length of paper to be pasted on the wall, said cutting means comprising a tubular guide having a guide slot and a 30 reciprocating element in the tubular member provided with a double edge knife, and means for reciprocating the element in one direction or the other for severing the paper.

A further object of the invention is to 35 provide yieldable connections between the handle and the machine proper, whereby the paper carrying rolls of the machine may accommodate themselves to the side wall or the ceiling of the room.

40 In practical fields, the details of construction may necessitate alterations falling within the scope of what is claimed.

The invention comprises further features and combination of parts, as hereinafter set 45 forth, shown on the drawings and claimed.

In the drawings:

Figure 1 is a view in side elevation of a wall paper hanging machine constructed in accordance with the invention.

50 Fig. 2 is a top plan view with parts broken away and parts in section.

Fig. 3 is a sectional view on line 3—3 of Fig. 1.

55 Fig. 4 is a sectional view on line 4—4 of Fig. 1.

Fig. 5 is a sectional view on line 5—5 of Fig. 2.

Fig. 6 is an enlarged detail sectional view of the tubular guide 53, showing the cutting knife therein, and a piece of wall paper 60 in position to be cut.

Fig. 7 is an enlarged detail sectional view on line 7—7 of Fig. 6, showing the double cutting edge of the knife.

Referring more especially to the drawings, 1 designates a casing or frame which may be of any suitable shape, preferably as shown in the drawings, and 2 designates a handle, which is tubular. The upper end of the handle has diametrically oppositely disposed apertures or openings 3 in its wall, and the extremity of the handle terminates in tubular forks 4, the ends of which have ears 5, to receive the pivots 6, whereby the forks are pivotally connected to the sides of the casing or frame. The lateral or transverse parts 7 of the forks have openings 8. A spring 9 has one end connected to an eye 10 of the handle and its other end to an eye 11 of the casing, which, together with another spring 12 having its ends similarly connected to the eyes 13 and 14 of the handle and casing respectively, act to provide yieldable connections between the casing and the handle. Such connections are provided to hold the casing in proper condition, whereby the wall paper applying rollers 15 and 16 may accommodate themselves to the side and ceiling walls of a room. A receptacle 17 is secured in any suitable manner at 18 to the wall 19 of the casing or frame 1. In fact, the receptacle 17 forms an integral part of said casing. A suitable cover 20 is hinged at 21 for closing the receptacle 17, there being a hasp 22 carried by the cover 20 and engaging the staple 23 (which is designed to receive a padlock, not shown) for holding the cover closed. The paste which is designed to be of a comparatively thick consistency, is placed in the receptacle 17, and a follower 24 is also mounted in the receptacle to feed the paste toward and through the opening 25 of said receptacle. In order that the follower shall closely fit the walls of the receptacle 17, a suitable 100 gasket 26 is riveted at 27 to the follower, and the marginal edge portions 28 of said gasket are bent over the edges of the follower and tightly engage the inner side and end walls of the receptacle. Threaded rods 110

105

29 are carried by the follower and pass through the cover. Springs 30 are mounted upon said rods between the cover and the follower, so that the follower will feed the 5 paste toward and through the opening 25. Winged nuts 31 are threaded upon the rods so as to regulate the expansion of the spring. A roll of wall paper 32 is mounted upon the shaft or spindle 33 of the casing or frame 10 1, and the paper from the roll passes over the rollers 34 (which are mounted upon the shafts or rods 35) over the roller 36 of the shaft 37, and thence over the rollers 15 and 16 of the shafts 38 and 39, respectively. Pivot 15 upon the nut headed lugs 40 of the opposite sides of the frame or casing 1, are the arms 41, in bearings of which, by means of the pins 42, the opposite ends of the shaft 43 are mounted. Springs 44 are connected 20 to the pins 45 of the opposite sides of the casing 1, and their other ends are connected at 46 to said arms 41. These springs serve to hold the roller 47 (which is journaled upon the shaft 43) against the figured or ornate 25 nated face of the wall paper at a point between the rollers 34, whereby the wall engaging face of the paper engages across the opening 25 of the receptacle 17, in order to receive its supply of paste. The opposite 30 side walls of the casing 1 are cut away, as shown at 48, to permit of a requisite movement of the shaft or rod 43 of the roller 47. Extending transversely of the casing 1 and having their pintles 49 engaging bearings of 35 the opposite sides of the casing 1, are rods 50. Adjustably secured upon the rod 50 by the set bolts 51 are cutting disks 52, the cutting edges of which are so beveled and overlapped, that the selvage edge of the paper, 40 as it is drawn from its roll and being applied to the wall, may be trimmed or severed. The cutting disks may be adjusted toward either side of the casing. A tubular guide 53 extends transversely of the casing and 45 has its opposite ends secured to the side walls of the casing, whereby its tubular passage may open through the side walls. The tubular guide has a guide slot 54, and mounted in the tubular passage of the tubular 50 guide is a carrier 55 provided with a double edged cutting knife 56. As shown in Figs. 6 and 7 the cutting knife is provided with double cutting edges 56^a and 56^b, and these edges are so constructed that when 55 the knife is moved in one direction or the other by imparting a steady and medium pull on the knife, one or the other of the cutting edges will cut or so score the paper as to permit the same to become severed 60 without tearing. A suitable cord 57 is attached to an eye 58 of the carrier 55 and passes through one of the forks 4 of the handle. A second cord 59 is attached to an opposite eye 60 of said carrier and passes 65 through the other fork 4. These two cords 57 and 59, respectively, pass through the openings 8 of the forks, and then through the openings 3 of the handle, and at the lower end, not shown of the handle, the other ends not shown of said cords merge 70 together to form a loop. The cords 57 and 59, where they leave the openings of the opposite ends of the tubular guide, engage over the arms 61, which have smooth surfaces in order to minimize the wear and tear on the 75 cords. In using the machine, paper sufficient to pass over the rolls 15 and 16 with paste thereon is pulled from the roller paper, the paste having been applied by passing over the opening 25. The paste containing side of the paper is then applied either to the base of the side wall or at one end of the ceiling, then the machine is rolled over the wall the paste being applied at the same time and the selvage trimmed. When the 80 machine reaches the top of the side wall or the other end of the ceiling, the operator pulls either one of the cords 57 and 59, thereby imparting a reciprocating motion to the knife carrier, the knife acting to sever the 85 requisite length of paper for the wall. 90

The invention having been set forth, what is claimed as new and useful is:—

1. In a wall paper hanging machine, a casing, wall papering rollers journaled therein, said casing having means to support a roll of wall paper and provided with a paste receptacle having a paste outlet opening over which said paper passes, a spring tensioned roller bearing on the paper and holding it 95 over said opening, whereby the paste may adhere thereto.
2. In a wall paper hanging machine, a casing, wall papering rollers journaled therein, said casing having means to support a roll 100 of wall paper and provided with a paste receptacle having a paste outlet opening over which said paper passes, a spring tensioned roller bearing on the paper and holding it over said opening, whereby the paste may 105 adhere thereto, and means for feeding the paste toward and through the outlet opening on to the paper.
3. In a wall paper hanging machine, a casing, wall papering rollers journaled therein, said casing having means to support a roll of wall paper and provided with a paste receptacle having a paste outlet opening over which said paper passes, a spring tensioned roller bearing on the paper and holding it 110 over said opening, whereby the paste may 115 adhere thereto, and means for feeding the paste toward and through the outlet opening on the paper, said feeding means comprising a follower in said receptacle provided with a gasket riveted to its face, said gasket having its marginal portions bent over the edges of the follower and engaging the inner faces of the sides of the receptacle, threaded guide rods on the follower pen- 120 125 130

trating through and guided in the cover of the receptacle, a cover for said receptacle, springs upon the rod between said cover and the follower, and thumb nuts threaded on 5 the rods and adapted to be adjusted, whereby the expansion of the springs will act to feed the paste toward and through the opening.

4. In combination with a wall paper hanging machine, a casing, a hollow handle having hollow forks pivoted to said casing, said casing having a transverse tubular guide provided with guide slots, a carrier in said tubular guide and provided with a doubled 15 edged knife extending through and guided

in the slot, a pair of cords connected to opposite ends of the carrier and passing through the tubular forks and brought together and passed through the hollow handle, whereby, as one or the other of said 20 cords is pulled, the carrier is moved in one direction or the other.

In testimony whereof I have signed my name to this specification in the presence of two subscribing witnesses.

LEWIS H. HITCHCOCK.
